MACHINE FOR MAKING BITUMINOUS
EMULSION

Leon R. MacKenzie, Des Moines, Iowa, assignor
to L. R. MacKenzie Incorporated, Tulsa, Okla.,
a corporation of Delaware

Application March 2, 1931, Serial No. 519,417

11 Claims. (Cl. 134—1)

The purpose and aim of this invention is to provide a machine for making a stable liqueous emulsion of a bituminous substance either liquid or semi-liquid or capable of becoming liquid, such as asphalt, and particularly a machine adapted to the process covered by my co-pending application, filed October 30, 1930, Serial No. 492,169, now Patent Number 1,795,226.

This machine is peculiarly adapted for carrying out a continuous process of succession of steps beginning with the introduction of hot liqueous bitumen and an emulsifying agent, at proper temperatures, to a closed chamber and forming a primary bitumen external phase emulsion which is then inverted to form a secondary internal phase emulsion. The secondary emulsion is then subjected to a stretching, sub-dividing and rolling operation between elongated and converging relatively moving surfaces, whereby the coarse emulsion is changed to one of finer form, and a variation of sizes of particles is produced. Thereafter, the fine tertiary emulsion is subjected to centrifugal action to remove air bubbles and to reduce it from a foamy to a more fluid state, as well as to increase the thoroughness of the mixing and the completeness of dispersion.

Included within the scope of this invention is the object of adjustability of one of the coating surfaces relative to the other for the purpose of changing the spacing between said surfaces and thereby regulating the size of the particles of bitumen in the resulting emulsion.

Another object of the invention is to provide an improved construction for a machine for making a liqueous emulsion of a bituminous substance such as asphalt, which emulsion will be sufficiently stable so that it can be handled, stored, and used under ordinary conditions.

With these and other objects in view my invention consists in the construction, arrangement and combination of the various parts of my device, whereby the objects contemplated are attained, as hereinafter more fully set forth, pointed out in my claims, and illustrated in the accompanying drawings. Although the invention is susceptible of a variety of embodiments it is unnecessary to fully describe and illustrate all possible forms in order to give a full understanding of the invention both from its structural and functional standpoints. Accordingly, I have illustrated several preferred and desirable embodiments of the invention in the accompanying drawings, in which:

Figure 1 is a perspective view of a machine embodying one form of my invention.

Figure 2 is a longitudinal section of the same. As shown particularly in this view, this form of the machine employs two substantially cylindrical surfaces, one being arranged for rotation within the other and being slightly tapered to form an elongated converging annular space, one member being adjustable longitudinally with relation to the other so as to provide means for regulating the spacing of the surfaces and the resultant fineness of the emulsion produced.

Figure 3 is a transverse section on the line 3—3 of Figure 2.

Figure 4 is a longitudinal section illustrating a different form of machine in which two substantially conical coating surfaces are employed, one conical member being arranged for rotation within the other. This form of the machine also embodies a jacket for live steam, whereby the interior of the machine may be heated.

Figure 5 is a cross section on the line 5—5 of Figure 4.

Figure 6 is a cross section on the line 6—6 of Figure 4.

Figure 7 is a longitudinal section illustrating a portion of a machine somewhat similar to that shown in Figure 4, but modified with respect to the mixing chamber or zone of formation of the primary emulsion, this machine being equipped with an interrupted spiral blade mounted for rotation in the elongated chamber, the initial portion of said blade acting as a wiping and equalizing member and the longer terminal portion acting as an agitating and emulsion advancing means.

Figure 8 is a similar view showing a further modified form of machine having a different form of a spiral rotary member which combines the functions of an agitating member and a grinding member in coaction with the walls of a chamber which gradually increases in diameter.

Figure 9 is a cross section of a machine of still further modified form in which the rotary member is eccentrically mounted within the chamber for producing a converging effect of the space between the coating surfaces. This machine also embodies a different means for producing centrifugal action with respect to the completed emulsion.

Figure 10 is a perspective view illustrating a modified form of frusto-conical arbor grinding member. This member is of the same general type as the corresponding member of the machine illustrated in Figure 4, but is modified with respect to a series of tapering grooves extending longitudinally of its surface.

Figure 11 is a detail longitudinal section of a portion of the arbor grinding member illustrated in Figure 10, and the surface with which it contacts. This view illustrates particularly the fact that the tapering groove formed in the surface of the arbor grinding member affords a different degree of convergence relative to the coacting surface, than is afforded by the general surface of the arbor grinding member with respect to 5 said coacting surface.

Various kinds and forms of emulsions may be made with machines embodying the present invention, and with bitumen of any desired state of hardness or ductility. The emulsions may be 10 made with any reasonable and practical relative volumes of bitumen and the emulsifying agent, which will hereinafter be referred to as "emulsifier". A further advantage resides in the speed and economy of production which may be had.

20 I have found that a very important characteristic of the machine is embodied in the use of two closely approximated surfaces of elongated character or extent, at least one of which is rotated relative to the other, and which preferably converge toward the outlet of the space between them. These surfaces, which may or may not be serrated or otherwise deformed or roughened, act to stretch, sub-divide and roll the particles of bitumen into progressively finer form 25 and also act to increase the dissemination, dispersion and diffusion of the bituminous particles through the emulsifier and thus produce the desired type of emulsion.

The spaced surfaces may be of different shapes 30 and formations and may be embodied in machines of varied constructions. In the accompanying drawings I have illustrated a number of different types of machines as examples of different embodiments of my invention.

40 In the construction according to Figures 1, 2 and 3, I have employed the numeral 10 to designate a suitable base upon which is mounted or formed a suitable casing member 12 which preferably is substantially cylindrical.

45 One end of the casing is formed by a separate plate 14 which is fitted snugly to the member 12 and secured in place in any suitable manner, as by cap screws 16.

The rigid end wall of the casing member 12 is 50 formed with a tubular extension 18 of less diameter than and communicating with the interior of the casing.

The tubular extension 18 is interiorly threaded and a sleeve 20 is adjustably mounted therein 55 and extends within the inner casing member 12. The sleeve 20 is open at its inner end and is formed at its outer end with an angular wrench-receiving or cap portion 22 by means of which it may be adjusted within the tubular extension 18 and the wall of the casing.

The tubular extension 18 preferably is split longitudinally on one side by means of a slot or kerf 24 opening to its outer end and is formed with a pair of ears 26 and 28 on opposite sides 65 of the outer end of said kerf.

A clamping lever 30 is provided and is formed with a right-angled stem 32 turnably mounted in one of the ears such as 28 and having threaded engagement with the other of said ears such as

70 26. When the clamping lever 30 is turned in one direction manually it permits the ears 26 and 28 to spread apart slightly so that the sleeve 20 may be adjusted longitudinally therein by turning it with a wrench or the like. When the lever 30 is 75 turned in the other direction, the threaded en-

gagement of its stem 32 causes the ear 26 to be drawn toward the ear 28 so that the split tubular member is clamped tightly upon the sleeve 20 and rotary movement of the latter member is prevented.

5 Rotatably mounted in the casing 12 and extending within and substantially throughout the length of the sleeve 20 is an arbor 34. The arbor 34 is formed with a reduced journal 36 which is mounted for rotation in a bearing 38 in the removable end member 14 of the casing.

A prime mover such as an electric motor 40 is mounted on the base 10 and its armature shaft 15 is operatively connected by a coupling sleeve 44 with the journal 36 of the arbor.

The interior wall of the sleeve 20 and the exterior surface of the arbor 34 provide the two elongated coacting surfaces which constitute a distinctive feature of my invention. As here shown, the interior surface of the sleeve 20 is truly 20 cylindrical while the outer surface of the arbor 34 is slightly tapered. In other words, the arbor 34 fits quite closely within the sleeve 20, but is spaced a slightly greater distance therefrom at its outer than its inner end, thus providing a 25 converging annular space between these members.

The arrangement, whereby a slightly tapered member is mounted within and slightly spaced from a member having an internal cylindrical 30 surface, also permits of some adjustment of the relative spacing of the two surfaces by adjusting the members axially. This adjustment is accomplished, as previously indicated, by the threaded mounting of the sleeve 20 within the 35 casing 12 and its extension 18 and the adjustment when made is maintained by means of the clamping lever 30.

The arbor 34 is formed at its inner end with a peripheral flange 46 which rotates in substantial contact with the inner face of the casing end member 14 and is normally spaced somewhat from the inner end of the sleeve 20.

The arbor 34 is formed at its outer end with an outwardly opening recess or cavity 48, which 45 preferably is of substantially frusto-conical shape and formed with a long and gradual taper. An inlet tube 50 is threadedly mounted through the outer end of the sleeve 20 and has its inner end projecting a substantial distance within the recess 48 of the arbor.

The outer end of the inlet tube 50 is suitably connected, as by means of a packing gland 52, with a Y 54, the two branches of which are connected, as by means of packing glands 56 and 55 58, with feed pipes 60 and 62 respectively.

The two substances to be acted upon, namely the liqueous bitumen and the emulsifier, are supplied to the machine through the feed pipes 60 and 62 from suitable containers, which are not 60 shown in connection with this particular form of machine although they are shown in the machine illustrated in Figure 5. These containers may be in the nature of pressure tanks, whereby the substances may be introduced to the machine 65 under pressure and they should also be equipped with means for preheating the substances separately to the desired temperatures.

In lieu of or in addition to pressure at the supply end, either by pressure in the supply tanks 70 or by means of pumps communicating with the supply pipes, the substances in the machine may be subjected to suction or pulling force at the outlet end of the machine for causing them to travel therethrough.

The amount and rapidity of flow of the two substances through the pipes 60 and 62 may also be varied and controlled by suitable controlling means such as valves and/or flow meters, not shown in connection with the present form of the machine.

The two substances, namely the liqueous bitumen and the emulsifier, are thus introduced through the pipes 60 and 62 to the Y 54, which 10 constitutes a closed, confined receiving or mixing chamber in the present form of the machine.

At the instant when the bitumen meets the emulsifier there is a foaming action which greatly increases the volume of the mixture and 15 spreads the bitumen into thin films, forming a coarse or a rough emulsion with the bitumen as the external phase—in other words, drops of emulsifier surrounded by films of bitumen constituting a primary emulsion. The foaming, 20 frothing action serves to stretch the films of bitumen. The primary emulsion is then immediately removed from the zone of formation and is subjected to agitation whereby the films of bitumen are broken up into minute particles and 25 are thoroughly dispersed and diffused. This produces a coarse or rough emulsion with the bitumen as the internal phase. In other words, the emulsion is inverted and this secondary emulsion consists of particles of bitumen surrounded 30 by films of the emulsifier.

Due to the forces which cause the substances to travel through the machine, the primary emulsion is immediately carried out of the Y 54 or mixing chamber through the pipe 50 and is received into the recess 48 of the arbor 34. The emulsion is then forced to travel in a reverse direction out of said recess and around the end of the tube 50, which is sufficiently spaced from the walls of the recess to permit such outward 40 travel without clogging or excessive back pressure.

It will be understood that the forcible introduction of the primary emulsion to the recess 48 and its removal therefrom by reverse travel causes 45 considerable agitation of the substance so that the emulsion becomes inverted to form a relatively coarse internal phase emulsion, or in other words, particles of bitumen surrounded by a film of emulsifier.

The coarse or secondary emulsion with bitumen as the internal phase is now caused to travel through the close elongated space between the surfaces of the sleeve 20 and the arbor 34, the latter member being rotated by its connections 55 with the motor 40. These coacting surfaces act to stretch, sub-divide, roll and spread the particles of bitumen through the emulsifier, and thus form a tertiary emulsion. The space between these surfaces is such as to promote the stretching, 60 sub-dividing, spreading, rolling, diffusing and mixing action, and to that end the surfaces may be suitably serrated or otherwise deformed or roughened.

The fineness and uniformity of the finished 65 product is controlled to considerable extent, both by the size and character of the space between the surfaces and by the speed of the movement of the surfaces with respect to each other. It is desirable to have the annular space between these 70 surfaces slightly tapered from front to rear so that there is a constant decrease in the space between the surfaces as the emulsion passes between them. This is accomplished by the tapered formation of the arbor 34 and it may be regulated by longitudinal adjustment of the sleeve 20.

Upon leaving the annular space between the surfaces the emulsion is discharged against the face of the peripheral flange 46 of the arbor and is thrown outwardly by centrifugal force toward the wall of the casing 12. This accomplishes a re-mixing action and also causes the entrapped air to be released so as to render the emulsion more liquid. This centrifugal action also tends to exert a pull on the emulsion stream, thus increasing flow.

The emulsion is then discharged from the casing 12 through a substantially tangential outlet 70 located at the bottom of the casing. From the outlet the emulsion may be received into any suitable receptacle or container where it preferably is rapidly cooled to normal temperature, by any suitable means, to increase stability, after which it is ready to be stored or shipped.

After the emulsion has reached this condition it is, and remains, more uniform and stable 20 through any of the usual conditions of handling, shipping or storing than any of the emulsions of which I know, and will still break down from the emulsion form when spread into thin films, in shorter time and under conditions which are 25 most desirable from the standpoint of practical use. Moreover, the characteristics of the bitumen are not substantially altered, unless this is done deliberately, and the relative volumes of the materials making up the emulsion remain constant 30 throughout the process carried on by the operation of this machine.

I purposely make use of the formation of the original or primary bitumen external phase emulsion because I have found that this is advantageous in breaking the bitumen into films and that the formation of this film in the thinnest form is facilitated by producing this primary emulsion at a preferred combining temperature. Proper regulation of combining temperature will 40 produce maximum frothing or foaming action, and thus maximum thinness of the film. By producing thinner film at this stage, the amount of grinding necessary for securing any necessary fineness of particles is reduced, and the requisite 45 fineness is secured with more certainty.

The immediate removal of the emulsion from the zone of formation before the bitumen can 50 agglomerate and bringing about the inversion of phase without changing the relative proportions of the ingredients, is also important.

Then by causing the secondary emulsion to pass between the elongated surfaces for the grinding action, the coarse emulsion will be changed to one of finer form. The passing of the material 55 between converging moving surfaces causes a greater variation of sizes than would otherwise result, thus making for low voidage between bitumen particles and permitting maximum bitumen content as well as making for minimum surface 60 area and thereby permitting the use of a minimum of emulsifier. These results are attained without sacrifice of fluidity.

In the form shown in Figures 4, 5 and 6, like 65 parts are designated by the same numerals, except as otherwise indicated.

In this form two frusto-conical coacting surfaces are employed, the one being the internal surface of a portion 72 of the casing, and the other being the external surface of an arbor member 74 splined on the arbor shaft 36.

In this type of machine a chamber 76 is formed at the initial end of the machine itself, this chamber being of cylindrical form and being closed at its end by a combined closing plate and bearing 75

member 78, which provides a bearing at one end of the shaft 36 and is held in place by means of cap screws 80.

In Figure 5 there are shown the two pressure 5 containers for the liqueous bitumen and the emulsifier, these containers being designated by the numerals 82 and 84. From the containers pipes 86 and 88 lead to and communicate with opposite sides of the chamber 76 of the machine and are 10 equipped with suitable controlling valves designated as 90 and 92 respectively.

The two liqueous substances are introduced at proper temperatures and in suitable quantities as controlled by the valves 90 and 92 to the 15 chamber 76 where the primary or external phase emulsion is formed.

The space at the initial end of the chamber 76 or adjacent to the inlet means 90 and 92, constitutes the zone of formation within which 20 foaming action of substances takes place and the primary emulsion is formed, and from which it is immediately withdrawn and subjected to agitation.

This is accomplished by a spiral blade 94 on 25 the shaft 36 in the terminal portion of the cylindrical chamber 76.

This agitation causes the inversion of the external phase emulsion to an internal phase emulsion of coarse form, and this secondary 30 emulsion is reduced by the coating surfaces of the members 72 and 74 to the fine emulsion of the final or tertiary form.

The centrifugal action upon the emulsion is produced by a plate 96 splined to the shaft 36 35 within the enlarged cylindrical portion 14 of the machine. As here shown, the plate 96 is spaced from the frusto-conical arbor member 74 and is provided with a series of fins 98 on its adjacent face which serve to cause rapid forward movement and amplified centrifugal action on the emulsion emerging from the annular space between the surfaces.

It will be noted from Figure 4 that the taper of the internal surface of the member 72 is different from the taper of the arbor member 74 to produce a convergence of the space between these members. The spacing between these coating surfaces may be adjusted by means of an adjusting nut 100 on the shaft 36 threaded into 50 a boss 102 on the end plate 14 and bearing at its inner end against the centrifuging plate 96. A lock nut 104 is provided for fixing and holding the adjustment when made.

If desired, a universal joint of common form, 55 designated generally by the numeral 106 may be interposed between the motor shaft 42 and the arbor shaft 36 for the purpose of compensating for variation in alignment of the shafts and also for permitting a slight longitudinal adjustment 60 of the shaft 36 by means of the adjusting nut 100.

It may also be desirable to provide means for maintaining the temperature of the machine and particularly of the substances therein at a relatively high point and for that purpose I have 65 formed the walls of the machine, including the mixing chamber 76, the tapered portion 72 and the enlarged cylindrical portion 12, with a jacket 108 to which live steam may be introduced by means of a pipe 110. (See Figure 6.) Water of 70 condensation may be removed from the steam jacket through an exhaust pipe 112, located near the discharge 70 for the bitumen.

In the form shown in Figure 7 the machine is quite similar to that just described, but the chamber to which the liqueous substances are intro-

duced is considerably elongated and is designated by the numeral 114.

In this form the supply pipes 86 and 88 preferably are not in transverse alignment. The pipe 88 through which the emulsifier enters is located at the extreme initial end of the chamber 114, while the pipe 86 for the liqueous bitumen is spaced longitudinally therefrom a suitable distance. Mounted on the shaft 36 within the chamber 114 is an interrupted spiral blade. The initial portion of this blade is designated by the numeral 95 and it acts as a wiper for the purpose of removing the liqueous substances from the outlets of the pipes 88 and 86 which are located respectively at the opposite ends of the blade 15 95. In other words, the wiper blade 95 takes alternate quantities of emulsifier and liqueous bitumen and causes them to be mixed in the initial end of the chamber. It serves to keep clear the outlets to the supply pipes and equalizes the 20 quantities of liqueous substance going to form the primary emulsion.

The second and longer portion of the spiral 25 is an agitating blade spaced from the first blade 95 and designated by the numeral 116. The blade 116 acts upon the emulsion after it leaves the initial end of the chamber and causes a thorough and complete agitation for completely transforming the emulsion into the secondary 30 stage before it passes to the annular space between the surfaces of the members 72 and 74. In other words, provision is made in the elongated chamber 114 for equalizing the quantities of liqueous substances and for more thoroughly 35 agitating the emulsion before it is subjected to the grinding and tearing action of the coating surfaces.

In Figure 8 there is shown a machine including a base 10 upon which is mounted an elongated tapered casing 118 within which an arbor 40 shaft 36 is arranged for rotation. At the initial or smaller end of the casing 118 are arranged the supply pipes 86 and 88 for introducing the liqueous substances.

Formed on or fixed to the shaft 36 is a tapered 45 member designated generally by the numeral 120 and this member combines the functions of agitating the emulsion and furnishing the coating grinding surfaces.

The member 120 has a spiral formation 50 throughout a considerable portion of its length, whereby there are produced relatively narrow spiral surfaces 122 coating with the inner surface of the casing 118 and also a spirally arranged recess 124. The spiral surface 122 preferably approaches gradually more closely to the inner surface of the casing member to produce the converging surfaces which have been previously discussed at considerable length.

The spiral recess 124 begins at a point spaced 55 suitably from the supply pipes 86 and 88 and gradually decreases in depth toward the larger end of the rotating or arbor member 120.

The initial end of the casing 118 serves as a small substantially closed mixing chamber for the 60 liqueous bitumen and the emulsifier, wherein is formed the primary or external phase emulsion. The primary emulsion is immediately acted upon and withdrawn from the mixing chamber and is agitated by the rotating spiral portion of the 65 member 120 for inverting it to the secondary 70 phase emulsion.

The emulsion as it travels through the casing 75 118 is subjected not only to agitation but also to the grinding action between the surfaces 122 and 75

the internal surfaces of the chamber and finally by the base or enlarged and elongated portion of the member 120 for reducing it to its fine or tertiary stage.

- 5 The spiral surfaces 122 of the rotating member may be formed with a series of spirally arranged grooves 126 which assist in the function of agitation, and in carrying the emulsion to and distributing it throughout the spiral surfaces 10 122. The grooves 126 also constitute roughened surfaces for the spiral portion 122, and in addition they may be utilized either for retarding or accelerating the flow of emulsion, depending upon the direction of rotation of the member 120 and 15 the direction of inclination of said grooves, as will be readily understood.

- Figure 9 discloses a still different type of machine including a substantially cylindrical casing 128 in which a rotor or arbor member 130 is arranged for rotation. The member 130 is cylindrical and fits snugly within the casing 128, but is arranged slightly eccentric thereto, whereby the space between their surfaces gradually converges in the direction of rotation and toward 20 the discharge port 132.

- The space between the casing 128 and rotary member 130 is enlarged at one side of the machine to form an inlet and mixing chamber 134 with which the supply pipes 136 and 138 communicate. Preferably one of the pipes such as 30 136 communicates with the mixing chamber 134 slightly in advance of the other pipe such as 138, with respect to the direction of rotation of the member 130, so that there will be a preliminary agitation of the substance entering through 35 the first mentioned pipe.

- The primary external phase emulsion is formed in the chamber 134 and is immediately withdrawn therefrom by pressure or suction or both and by 40 the action of the rotating member 130, and is thereby agitated to form the secondary phase emulsion of coarse form. This emulsion immediately proceeds through the space between the casing wall 128 and the rotating member 130 and 45 is subjected to the stretching, rolling and spreading action which reduces it to the tertiary stage before it passes through the outlet 132.

- In this form of the machine a centrifuging plate 140 is carried and driven by a shaft 142 arranged 50 for rotation on an axis substantially at right angles to that of the member 130. The plate 140 faces the outlet port 132 of the casing and may be formed on its face with radial fins 144 for increasing the agitation and centrifugal action 55 of the plate 140, which is held in place by a closing plate 146 which also provides a bearing for the shaft 142 and is secured to the casing by means of cap screws 148.

- The emulsion which passes through the discharge port 132 is subjected to centrifugal action 60 by the plate 140 and its fins 144 and is discharged into a chamber 150 from which a pipe 152 leads the emulsion to the desired place of storage.

- 65 In Figures 10 and 11 there is shown a frusto-conical arbor grinding member 154 which may be substituted for the corresponding member which is shown for instance in Figure 4. The member 154, as here shown, is formed with a 70 series of circumferentially spaced, longitudinally arranged grooves, which preferably are of angular formation. The grooves 156 open to the initial end of the member 154 where they are of considerable depth but they decrease in depth toward the other end of the member and prefer-

ably taper out or merge into the surface thereof before reaching the larger or terminal end.

The surface of the grinding member 154 and its grooves 156 cooperate with a coacting surface such as 158 to provide an elongated aperture through which the secondary emulsion is caused to pass, as before stated. It will be observed that on account of the progressive decrease in depth of the grooves 156 there is provided a variation of convergence between coacting surfaces. That 10 is to say, the bottoms of the grooves 156 will present a different degree of convergence with respect to the surface 158 than that presented by the general surface of the member 154. Inasmuch as the deeper ends of the grooves 156 15 open to the smaller end of the rotating member 154, they greatly facilitate the introduction of the comparatively coarse secondary emulsion to the space between the surface of said member and the casing. From these grooves the emulsion is thrown out by centrifugal action of the rotor, against the smooth surface of the coacting member, thereby increasing the spreading and rolling action and assisting in the operation of reducing the emulsion to its finely dispersed phase. The decrease in depth of the grooves and the fact that they taper out before reaching the opposite end of the rotor, furnishes a sort of head or abutment against which the pressure at the initial end of the machine may 20 act and the continuous pressure back of the liquid material forces it toward the ends of the sloping grooves, insuring that the substance will be spread over a larger area of the coacting surfaces, and that none of the material will pass out 25 of the narrow aperture without being reduced to the desired state of fineness.

The longitudinally extending spirally arranged groove 124 of the form shown in Figure 8 accomplishes the same function.

If desired the surface of the member 154 may be formed with a series of kerfs or serrations 160 opening to the grooves 156 on the trailing edges thereof with respect to the direction of rotation. These kerfs or serrations constitute roughened surfaces for the grinding member. They serve to stretch and spread the particles of emulsion traveling from the grooves 156 to the narrower surface between members 154 and 158 as the former member is rotated.

It has been found that a machine having the characteristics set forth herein is very efficient for producing a bituminous emulsion possessing the desired properties of fineness and uniformity of texture and complete coating and enveloping of individual particles of bitumen with the emulsifying solution.

It is to be understood that any suitable and well known means may be employed for varying the speed of the prime mover to obtain desired speed of the grinding member.

It should also be noted that any suitable means, of which the steam jacket 108 is an illustration, may be employed for inducing and controlling proper temperatures within the machine, independent of the regulated temperatures of the liqueous substances entering into the emulsion.

It will be observed that in some forms of the machine, such for instance as the one shown in Figure 9, there is no separate member for agitating and advancing the primary emulsion, but that dependence for these functions is placed upon the rotary movement of the grinding member, which may, of course, be supplemented by pressure or

suction effect applied to the liqueous substances as previously referred to.

It is important to introduce or flow directly together the emulsifier and liqueous bitumen under pressure, into a confined and substantially closed mixing chamber which is free and clear and contains no agitating member. By so doing I purposely take advantage of the formation under such circumstances of the primary emulsion with bitumen as its external phase, and take advantage of the foaming, frothing action thus produced, and utilize this natural phenomenon for accomplishing the first step in a continuous emulsification process, namely, the formation of thin films rather than formation of threads. The use of continuous and substantial pressure behind the liquid materials is important in procuring the foaming and frothing action for the forming of the primary emulsion in the substantially enclosed mixing chamber, and also for immediately removing the primary emulsion from the zone of formation.

Subjecting bituminous emulsion to centrifugal action, immediately after its formation, is also important. This step reduces the hot emulsion from a foamy to more fluid state, releases air and increases thoroughness of mixing and dispersion, so that the emulsion will be stable and remain fluid when cooled.

30 It is obvious from the various illustrations herein shown and described that a considerable variety of constructions may be employed for accomplishing this purpose. In other words, the closely approximated relatively moving surfaces 35 may be of any desired shape and arrangement, and I do not desire to be understood as limiting myself to the specific forms herein shown and described. Furthermore, the convergence of the surfaces may be secured in different ways, some 40 of which are illustrated in the various embodiments herein shown and described.

I claim as my invention:—

1. A machine for making bituminous emulsion comprising a mixing chamber, separate means 45 for flowing directly together into said chamber liqueous bitumen and an emulsifier, whereby there is formed a primary emulsion with bitumen as the external phase, means for removing the emulsion from the zone of formation and agitating it to form a secondary emulsion with bitumen 50 as the internal phase, a pair of coacting, relatively movable surfaces between which the secondary emulsion is caused to pass for exerting a sub-dividing, rolling and spreading action thereon, whereby the particles are reduced in size and dispersion is increased, and flat disk means for subjecting the stream of emulsion to centrifugal action as it leaves the space between said surfaces.

60 2. A machine for making bituminous emulsion comprising a chamber, separate means for introducing to said chamber heated liqueous bitumen and an emulsifier whereby there is formed a primary emulsion with bitumen as the external phase, means for immediately removing said primary emulsion from the zone of formation and causing an agitation whereby it is converted to a secondary emulsion with bitumen as the internal phase, an elongated aperture between two surfaces 65 through which the emulsion is caused to pass, means for moving one surface relative to the other to subject the emulsion to spreading and rolling action, and a flat disc-like member adjacent and extending across the outlet of said aperture, moving in a plane angular to the axis

of said aperture, for engaging the emulsion as it emerges from said aperture and subjecting it to centrifugal action.

3. A machine for forming a bituminous emulsion comprising a casing having a substantially closed mixing chamber, means for flowing directly together into said chamber liqueous bitumen and an emulsifier for forming a primary emulsion with bitumen as the external phase, positive means being provided for immediately withdrawing the primary emulsion from the zone of formation and agitating it to convert into a secondary emulsion with bitumen as the internal phase, an arbor grinding member rotatably mounted in said casing and having a surface 10 coacting with the surface thereof for forming an elongated aperture through which the secondary emulsion is caused to pass for spreading and rolling the particles, for reducing them and increasing dispersion, one of said surfaces being 15 inclined relative to the other to produce a convergence of the elongated aperture toward its outlet end, and movable means arranged transversely only of said aperture and having a face 20 extending across its outlet end for subjecting the emerging emulsion to centrifugal action.

25 4. A machine for forming a bituminous emulsion comprising a casing having a substantially closed mixing chamber, means for flowing directly together into said chamber liqueous bitumen and an emulsifier for forming a primary emulsion with bitumen as the external phase, means being provided for immediately withdrawing the primary emulsion from the zone of formation and 30 agitating it to convert into a secondary emulsion with bitumen as the internal phase, an arbor grinding member rotatably mounted in said casing and having a cylindrical surface coacting with the interior surface thereof for forming an elongated cylindrical aperture through which the secondary emulsion is caused to pass for spreading and rolling the particles, for reducing them and 35 increasing dispersion, one of said surfaces being inclined relative to the other to produce a convergence of the elongated aperture toward its outlet end, said grinding member being formed with a groove in its surface, which groove decreases in depth from the initial end of the member and lengthwise of its axis, whereby a 40 differently converging spacing is procured with respect to said coacting surface.

45 5. A machine for forming bituminous emulsion comprising a chamber, means for introducing to said chamber liqueous bitumen and an emulsifier whereby an emulsion is produced, a pair of surfaces producing an elongated aperture through which the emulsion is caused to travel, means for moving one surface relative to the other, and a rotating disk transverse of said aperture for subjecting the emulsion to centrifugal action as it leaves said aperture.

55 6. A machine for making bituminous emulsion comprising a pair of closely approximated surfaces consisting of a stator and a rotor, means for introducing liqueous bitumen and an emulsifier to the space between said surfaces where they are subjected to a sub-dividing, spreading and rolling action, and a disk having a surface extending across the outlet end of said space for subjecting the emerging stream of emulsion to centrifugal 60 action immediately after it leaves the space between said surfaces.

7. A machine for making bituminous emulsion comprising a mixing chamber, separate inlet means for flowing directly together into said 65

- chamber, under pressure, liqueous bitumen and an emulsifier, whereby there is formed a primary emulsion with bitumen as the external phase, wiping means moving across the respective inlet means for picking up uniform quantities of the substances to effect maximum frothing action, means for immediately removing the primary emulsion from the zone of commingling and causing agitation, an elongated, narrow converging aperture between two surfaces through which the substance is caused to pass, one of said surfaces being formed with a groove decreasing gradually in depth lengthwise of the axis of rotation, means for moving one surface relative to the other to subject the substance to sub-dividing, rolling and spreading action, means for adjusting one surface relative to the other to regulate the size of said aperture, and means for subjecting the stream of emulsion to centrifugal action as it leaves the space between said surfaces. 5
- 5 for picking up uniform quantities of the substances to effect maximum frothing action, means for immediately removing the primary emulsion from the zone of commingling and causing agitation, an elongated, narrow converging aperture between two surfaces through which the substance is caused to pass, one of said surfaces being formed with a groove decreasing gradually in depth lengthwise of the axis of rotation, and a flat disk for moving one surface relative to the other to subject the substance to sub-dividing, rolling and spreading action. 10
- 10 between two surfaces through which the substance is caused to pass, one of said surfaces being formed with a groove decreasing gradually in depth lengthwise of the axis of rotation, and a flat disk for moving one surface relative to the other to subject the substance to sub-dividing, rolling and spreading action. 15
- 15 8. A machine for making bituminous emulsion comprising a mixing chamber, separate inlet means for flowing directly together into said chamber, under pressure, liqueous bitumen and an emulsifier, whereby there is formed a primary emulsion with bitumen as the external phase, means for immediately removing the primary emulsion from the zone of commingling and causing agitation, an elongated, cylindrical, narrow, converging aperture between two surfaces through which the substance is caused to pass, one of said surfaces being formed with a groove 20 decreasing gradually in depth lengthwise of the axis of rotation, means for moving one surface relative to the other to subject the substance to sub-dividing, rolling and spreading action, means for adjusting one surface relative to the other to regulate the size of said aperture, and means for subjecting the stream of emulsion to centrifugal action as it leaves the space between said surfaces. 25
- 20 9. A machine for making bituminous emulsion comprising a mixing chamber, separate inlet means for flowing directly together into said chamber, under pressure, liqueous bitumen and an emulsifier, whereby there is formed a primary emulsion with bitumen as the external phase, wiping means moving across the respective inlet means for picking up uniform quantities of the substances to effect maximum frothing action, means for immediately removing the primary emulsion from the zone of commingling and causing agitation, an elongated, cylindrical, narrow, converging aperture between two surfaces through which the substance is caused to pass, one of said surfaces being formed with a groove 30 decreasing gradually in depth lengthwise of the axis of rotation, means for moving one surface relative to the other to subject the substance to sub-dividing, rolling and spreading action, means for adjusting one surface relative to the other to regulate the size of said aperture, and means for subjecting the stream of emulsion to centrifugal action as it leaves the space between said surfaces. 35
- 30 10. A machine for making bituminous emulsion comprising a mixing chamber, separate inlet means for flowing directly together into said chamber, under pressure, liqueous bitumen and an emulsifier, whereby there is formed a primary emulsion with bitumen as the external phase, means for immediately removing the primary emulsion from the zone of commingling and causing agitation, an elongated, cylindrical, narrow, converging aperture between two surfaces through which the substance is caused to pass, one of said surfaces being formed with a groove 40 decreasing gradually in depth lengthwise of the axis of rotation, means for moving one surface relative to the other to subject the substance to sub-dividing, rolling and spreading action, means for adjusting one surface relative to the other to regulate the size of said aperture, and means for subjecting the stream of emulsion to centrifugal action as it leaves the space between said surfaces. 45
- 35 11. A machine for making bituminous emulsion comprising a mixing chamber, separate inlet means for introducing to said chamber, under pressure, liqueous bitumen and an emulsifier, wiping means moving across the respective inlet means for picking up uniform quantities of the substances to effect maximum frothing action, an elongated, cylindrical, narrow aperture between two relatively movable surfaces through which said substance is caused to pass for effecting a sub-dividing, rolling and spreading action, and means for subjecting the stream of emulsion to centrifugal action as it leaves the space between said surfaces. 50
